UNITED STATES PATENT OFFICE

103,870

DESIGN FOR A SIGN

Donald S. Freeman, Des Moines, Iowa

Application December 22, 1936, Serial No. 66,688

Term of patent 7 years

To all whom it may concern:

Be it known that I, Donald S. Freeman, a citizen of the United States and a resident of Des Moines, in the county of Polk and State of Iowa, have invented a new, original, and ornamental Design for a Sign, of which the following is a specification, reference being had to the accompanying drawing, forming part thereof.

I claim:
The ornamental design for a sign as shown.

DONALD S. FREEMAN.
